UNITED STATES PATENT OFFICE.

WILLIAM E. SMITH, OF ANSONIA, CONN., ASSIGNOR TO JOHN C. HOTCHKISS,
OF SAME PLACE, AND BURKARD GOODMAN, OF NEW YORK, N. Y.

LEVER-BUCKLE.

SPECIFICATION forming part of Letters Patent No. 315,177, dated April 7, 1885.

Application filed February 20, 1885. (No model.)

To all whom it may concern:

Be it known that I, WILLIAM E. SMITH, of Ansonia, in the county of New Haven and State of Connecticut, have invented a new 5 and useful Improvement in Lever-Buckles, of which the following is a specification.

My invention relates to lever-buckles commonly used for suspenders and other webbing, and which are composed of a plate having at 10 opposite sides ears which are bent over double, or into positions parallel with the main portion of the plate, and a lever which has its trunnion-bearings in said ears.

In my United States Letters Patent No. 15 304,870, dated September 9, 1884, is shown and described a buckle of the kind above referred to, in which the ears are depressed or set inward to form bearings for the lever-trunnions, which are held in such bearings by caps 20 consisting of separate pieces secured thereto.

The object of my present invention is to dispense entirely with the two separate caps, and to so combine the lever with said ears as not only to securely hold the lever in place, 25 but also to enable the lever to form a stay or tie-piece between the ears to prevent the ears from spreading.

The invention consists in a novel construction of the plate or frame and lever, and a 30 novel manner of combining and connecting them together, as hereinafter described, and pointed out in the claims, whereby the desired results are secured.

In the accompanying drawings, Figure 1 is 35 a back view of a buckle embodying my invention. Fig. 2 is a sectional view on the plane of the dotted line $x-x$, Fig. 1, looking toward the left hand of said figure. Fig. 3 is a sectional view of the buckle plate or frame alone 40 on the plane of the dotted line $y-y$, Fig. 1, the lever being omitted. Fig. 4 is a plan of the buckle. Fig. 5 is a view of the blank from which the plate or frame is formed. Fig. 6 is a view of the blank from which the lever is 45 formed; and Fig. 7 is a perspective view of the completed lever.

Similar letters of reference designate corresponding parts in all the figures.

A designates the plate or frame of the buckle, 50 which is made of sheet-brass or other sheet

metal. It may be of any ornamental shape desired, and, as here shown, is formed with an integral hook, a , and a spring-tongue, b , cut from the plate and deflected to bear against the inner side of the hook. At opposite sides 55 the plate has ears c , which are doubled or bent over and inward into positions parallel with the rear side of the plate. The inner edge portions of the ears c are stamped or deflected inward to form concave depressions d and minor depressions or offsets d' , extending 60 from the depressions d to the lower edges of the ears, and at the most distant edges of the depressions the ears are slit or have slots e . These slots greatly facilitate the formation of 65 the depressions d and d' , and the ears on the inner sides of the slits or slots are depressed, while on their outer sides they are not depressed.

In Fig. 5 I have represented a blank for the plate or frame, having formed in it the 70 slots e and the depressions d and d' , which are formed in the reverse side of the plate to that shown in Fig. 5, thereby producing raised portions or projections on the side or face shown in said figure. 75

B designates a lever, which is made from a blank of the form shown in Fig. 6. At the upper edge are serrations or teeth f , and at opposite sides are trunnions or pivots g , and beyond or at the outer ends of the trunnions 80 g are ears g' . The lever is to be bent on the dotted line * shown in Fig. 6, thereby giving it the form shown in Fig. 7.

The manner of combining the lever and plate will be best understood from Figs. 1 85 and 2. The lever is of a width to just drop into the depressions d , and its trunnions or pivots g rest in the bearings formed by the depressions d and project beyond them and under the portions of the ears c which are beyond or outside the slots e . The portions of the ears inward of the slots form bearings d for the lever-trunnions g , and the portions of the ears outside of said slots serve to retain the lever-trunnions in said bearings. The 90 portion of the lever below the trunnions bears against and is supported by the portions of the ears c below the bearings d , and is thereby prevented from dropping inward upon the web. The lugs or ears g' project inward be- 100

yond the outer edges of the depressed portions *d*, as best shown in Fig. 4, and enable the lever to serve as a tie-piece or brace connecting the ears *c* and preventing their spreading.

5. What I claim as my invention, and desire to secure by Letters Patent, is—

1. In a lever-buckle, the combination, with the plate provided with ears doubled or bent inward and slotted, and having the portions 10 of the ears inward of said slots depressed to form trunnion-bearings, of the lever having trunnions or pivots resting in said bearings and projecting beyond the slots and under the portions of the ears outside the slots, substantially as herein described.

15. 2. In a lever-buckle, the combination, with the plate *A*, provided with the ears *c*, having slots *e* and depressions *d*, forming trunnion-bearings, of the lever *B*, having trunnions *g*,

resting in said bearings, projecting under the 20 portions of the ears outside said slots, and provided with ears *g'*, which project inward on the outer sides of the depressed bearings *d*, substantially as and for the purpose herein described.

25. 3. In a lever-buckle, the combination, with a plate, *A*, provided with ears *c*, having slots *e* and the depressed bearings *d*, of the lever *B*, having trunnions *g*, which rest in said bearings and project under the portions of the ears 30 outside the slots, the lever bearing against and being supported by the portions of the ears below the bearings *d*, substantially as herein described.

WILLIAM E. SMITH.
